UNITED STATES PATENT OFFICE.

ALBERT JOHN HAMMOND, OF BEN LOMOND, CALIFORNIA.

DESIGN FOR A LAMP SHADE.

Application filed August 20, 1927. Serial No. 23,165. Term of patent 14 years.

To all whom it may concern:

Be it known that I, ALBERT JOHN HAMMOND, a citizen of the United States, and a resident of Ben Lomond, county of Santa Cruz, State of California, have invented a new, original, and ornamental Design for a Lamp Shade, of which the following is a specification, reference being had to the acpanying drawing, forming part thereof, and in which the figure is a perspective view of a lamp shade showing my new design.

I claim:

The ornamental design for a lamp shade, as shown.

ALBERT JOHN HAMMOND.
